Primary Examiner — Darlington Ly*Assistant Examiner* — Giang Hoang Tran(74) *Attorney, Agent, or Firm* — Alleman Hall & Tuttle LLP(57) **CLAIM**

The ornamental design for a chain guide for motorcycle as shown and described.

DESCRIPTION

FIG. 1 is a bottom, front and left side perspective view of a chain guide for motorcycle showing my new design;
 FIG. 2 is a front elevation view thereof;
 FIG. 3 is a rear elevation view thereof;
 FIG. 4 is a top plan view thereof;
 FIG. 5 is a bottom plan view thereof;
 FIG. 6 is a left side elevation view thereof;
 FIG. 7 is a right side elevation view thereof; and,
 FIG. 8 is a top, rear and right side perspective view thereof. The broken lines in the drawings illustrate portions of the chain guide for motorcycle that form no part of the claimed design.
